UNITED STATES PATENT OFFICE

172,480

FORK OR SIMILAR ARTICLE

Nicholas J. Silletti, Rockford, Ill.

Application February 15, 1954, Serial No. 29,037

Term of patent 14 years

(Cl. D44—29)

To all whom it may concern:

Be it known that I, Nicholas J. Silletti, a citizen of the United States of America, residing at Rockford, in the county of Winnebago and State of Illinois, have invented a new, original, and ornamental Design for a Fork or Similar Article, of which the following is a specification, reference being had to the accompanying drawing, forming part thereof.

In the drawing:

Fig. 1 is a top plan view showing my new design for a fork or similar article; and

Fig. 2 is a side elevational view thereof.

The dominant features of the design reside in the portions shown in full lines.

I claim:

The ornamental design for a fork or similar article, substantially as shown and described.
